UNITED STATES PATENT OFFICE.

FRANCIS KERNAN, OF UTICA, NEW YORK.

HEATING-FURNACE.

No. 802,295.

Specification of Letters Patent.

Patented Oct. 17, 1905.

Application filed June 12, 1903. Serial No. 161,138.

To all whom it may concern:

Be it known that I, FRANCIS KERNAN, a citizen of the United States, residing at Utica, in the county of Oneida and State of New York, 5 have invented new and useful Improvements in Heating-Furnaces, of which the following is a specification.

My invention relates to a heating-furnace, particularly adapted for burning soft or bituminous coal, and has for its object to supply to the fire and mix with the products of combustion a sufficient amount of heated air, so that the smoke and products are consumed.

The invention consists in constructing the 15 fire-door on its inner surface with an air-chamber into which the air is admitted and heated and is then distributed downwardly onto the surface of the fire.

My invention will be understood by reference to the drawings herewith, in which the reference-numerals of the specification indicate the corresponding parts in all the figures.

Figure I is a front elevation of the furnace with portions broken away. Fig. II is a vertical section at right angles to the preceding. Fig. III is an elevation of the inside of the feed-door enlarged. Fig. IV is a vertical section at right angles to the preceding. Fig. V is a top plan thereof. Figs. VI and VII are 30 respectively elevation and bottom plan of the flue-plate detached. Fig. VIII is a vertical section through one of the flues thereof.

In the drawings, 1 indicates the fire-box; 2, the dome; 3, the flues; 4, the ash-pit; 5, 35 the ash-pit door; 6, the grate; 7, the dust-flue; 8, the dust-damper; 9, the hand-hole; 10, the jacket, and 11 the clean-out door, of usual construction.

20 is the feed-door, having inlet 21 and inlet-damper 22, suitably regulated, as best shown in Fig. I, to admit a greater or less amount of air to the air-chamber 23, having contracted throat 24, formed by securing to the inside of the door the chamber-plate 26, 45 preferably vertically corrugated to give a greater heating-surface.

In the fire-box of the furnace is secured the flue-plate 28, formed with the flues 29, having their inner ends inclined slightly downwardly and so arranged that when the fire-door is closed it makes a tight joint with the flange 31. Above the fire-box and supported thereon is the dome 40, which with the fire-box forms the combustion-chamber 41 outside the 50 dome, and between it and the feed-door is ar-

ranged the mouthpiece 42, which may be made integral with the dome, if desired.

By my construction the air in a regulable amount enters the air chamber or reservoir in the door where it is held momentarily to be heated, and thence through the throat or outlet of the reservoir contracted to give a good draft is distributed or sprayed in a downward current uniformly over substantially the whole fire-surface, so as to be thoroughly mixed with the products of combustion and unconsumed gases, supplying sufficient oxygen to consume all such products, avoiding smoke, and economizing fuel.

My invention is simple and economical to manufacture, is easily attached to various forms of furnaces, and has the great advantage that there are few joints and connections, and all such joints are entirely inside the furnace and none of them in the air-chamber formed by the jacket around the furnace, so that in case of accidental leak there is no danger of gases escaping into the house; but they are all retained within the furnace and are consumed to pass up to the chimney with the remainder of the gases. While particularly adapted for use with soft coal, yet the furnace so constructed may be used with anthracite, preferably the smaller sizes, and other fuels.

I do not limit myself to the exact construction here shown, for the form may be varied without departing from the spirit of my invention.

Having thus described my invention, what I claim as new, and desire to secure by Letters Patent, is—

1. In a heating-furnace, the combination with the furnace and the feed-door, of a vertically-corrugated chamber-plate secured to the inner face of the door forming an enlarged air-chamber provided with an inlet in its upper portion through the door, a damper to said inlet, a finishing-plate secured to the door and fitted to the lower portion of the chamber-plate, to form a contracted throat and an outlet from the air-chamber, the flue-plate arranged within the fire-box and provided with substantially horizontal and downwardly-curved flues adapted to register with the air-chamber outlet, and a flange on the chamber-plate to make substantially a tight joint with the flue-plate, when the door is closed.

2. In a heating-furnace, the combination with the furnace, of the feed-door provided

with an air-chamber on its inner face, said chamber having an inlet through the door and an outlet to the fire, and a substantially horizontal flue-plate to receive in its flues the heated air from the chamber and to distribute it into the products of combustion over the surface of the fire, said flues having their inner ends inclined slightly downwardly, said flue-plate being arranged entirely within the

10 mouth and outside of the combustion-chamber, substantially as described and shown.

3. In a heating-furnace, the combination with the feed-door, of a chamber-plate secured to the inner face of the door forming

15 an enlarged air-heating chamber in its upper portion and a contracted throat along its lower margin, the door being provided with an air-inlet into the upper portion of the chamber, an inlet-damper to control the air

20 flowing in through the inlet, and a flue-plate arranged in the bottom of the mouthpiece and entirely within the mouthpiece, the flue-plate being formed with a series of flues adapted to register with the throat at their outer ends,

25 the outer portions of the flues being substantially horizontal.

4. In a heating-furnace, the combination with the feed-door, of a chamber-plate secured to the inner face of the door forming

30 an enlarged air-heating chamber in its upper portion and a contracted throat along its

lower margin, the door being provided with an air-inlet into the upper portion of the chamber, an inlet-damper to control the air flowing in through the inlet, and a flue-plate 35 arranged in the bottom of the mouthpiece and entirely within the mouthpiece, the flue-plate being formed with a series of flues adapted to register with the throat at their outer ends, the outer portions of the flues being substantially horizontal, and the inner ends of the flues being inclined slightly down, to distribute the inflowing heated air over substantially the entire surface of the fire, to mix with the products of combustion. 40

5. As a new article of manufacture, a separable flue-plate adapted to be arranged in the bottom of the mouthpiece of a heating-furnace, said flue-plate being formed with a concave inner margin, the metal adjacent to said 45 inner margin being inclined slightly down and the plate provided with a series of parallel ribs extending from its outer to its inner margin, forming flues when the plate is set in position.

In testimony whereof I have signed my name 50 to this specification in the presence of two subscribing witnesses.

FRANCIS KERNAN.
